RADIO RECEIVING APPARATUS

Original Filed Dec. 8, 1924

UNITED STATES PATENT OFFICE.

BYRON B. MINNIUM, OF CHICAGO, ILLINOIS, ASSIGNOR TO WALTER H. HUTE, OF CHICAGO, ILLINOIS.

RADIO RECEIVING APPARATUS.

Original application filed December 8, 1924, Serial No. 754,501. Divided and this application filed February 1, 1926. Serial No. 85,295.

This invention relates to radio receiving apparatus, and more particularly to apparatus of this kind having vacuum tube amplification. In radio frequency amplifier circuits of this kind there is a tendency toward the local setting up of sustained oscillation which, of course, may interfere with the proper operation of the apparatus, inasmuch as such action has a tendency to 10 interfere with the incoming signal, or even to entirely blanket the incoming signal, so to speak, and thereby prevent the proper operation of the apparatus.

This application is a division of my co-pending application, Serial No. 754,501 filed December 8, 1924.

Generally stated, therefore, the object of the invention is to provide a novel and improved circuit arrangement for preventing the above mentioned oscillation in radio frequency amplifier circuits, which is sometimes called a feed back of energy from the plate to the grid of the vacuum tube, and to thereby insure against any interference of this kind with the proper reception of the incoming signal.

More particularly, it is an object of this invention to provide a pair of simultaneously variable connected condensers, arranged in shunt to the tuning inductance whereby two arms of a Wheatstone bridge may be simultaneously adjusted so that the capacities in these two arms maintain a substantially fixed ratio for all adjustments thereof.

It is also an object to provide certain details and features of construction and combinations tending to increase the general efficiency and the desirability of a radio frequency amplifying arrangement of this particular character.

To the foregoing and other useful ends, the invention consists in the matters hereinafter set forth and claimed, and shown in the accompanying drawings, in which:

Fig. 1 is a diagram of a radio receiving apparatus involving the principles of the invention;

Fig. 2 is a simplified diagram, using the ordinary Wheatstone bridge arrangement, showing the theory and the mode or operation of the invention; and

Fig. 3 is a diagram showing the preferred form of the invention.

As thus illustrated, the hook-up or circuit arrangement shown in Fig. 1 is in a general way an ordinary one, involving a two-stage radio-frequency vacuum tube amplification. The aerial 1 may be of any suitable character and is grounded through the primary 2 of the transformer or repeating coil, as shown. The secondary coil 3 has one terminal connected to the grid 4 of the first vacuum tube, and has its other terminal connected to the condenser 5 of any suitable character. The other terminal of the condenser 5 is connected to the plate 6 of the vacuum tube, and the filament 7 of the tube has its terminals connected to the batteries shown at the right of the diagram, in the ordinary manner. The second stage of amplification is of similar character, it will be seen, and a description of the circuit arrangement of one vacuum tube will be sufficient.

For tuning purposes, two adjustable condensers 8 and 9 are connected in series between the terminals of the secondary coil 3, so that the capacity and inductance are in parallel, as shown. In addition, a tap 10 is taken from one terminal of the filament 7 and carried over to the middle point 11 of the capacity shunt thus formed in parallel with the secondary coil 3 of the transformer or repeating coil. The primary coil 12 of the next transformer or repeating coil, of the second stage of amplification, is connected in circuit as shown, so that the coil 3 is in the input circuit of the vacuum tube, while the coil 12 is in the output circuit of said tube.

With this arrangement there is a tendency toward oscillation, as previously stated, owing to a sort of feed back from the plate 6 to the grid 4, during the reception of the radio frequency signal, but with the

- arrangement shown, involving the use of capacities 5 and 8 and 9, and the capacity between the grid 4 and the plate 6, the harmful and undesirable oscillation is prevented. As shown by the Wheatstone bridge arrangement in Fig. 2, there is capacity in each arm of the bridge, so that all four arms of the bridge contain enough capacity to prevent the said feed back of energy from the plate to the grid of the vacuum tube. With such an arrangement, it is found that any electrical disturbance or voltage across the points 13 and 14 will have no effect upon the points 15 and 16 or input terminals. In other words, the Wheatstone bridge arrangement is balanced, so to speak, and the points 15 and 16 remain at the same potential, so far as any electrical disturbance across 13 and 14 is concerned. In this Wheatstone bridge arrangement, as shown, there is employed as one capacity for one arm or side of the bridge the grid-to-plate capacity 4 and 6, and the other three arms of the Wheatstone bridge have the condensers 5, 8 and 9 located therein, as shown and described. The capacities 8 and 9 are employed for tuning the input circuit of the vacuum tube, as these condensers are adjustable. The condensers 8 and 9 can be separately adjustable, or they can be mounted on the same shaft, or geared together, as indicated in Fig. 3, whereby the motion of one is governed by that of the other, so that the two condensers may be varied together by a single control, but preferably in such a way as to at least approximately maintain a constant capacity ratio.
- In the arrangement shown in Fig. 3, the condensers 8' and 9' have their rotatable elements 18 and 19 mechanically connected together, as schematically shown by the dash line 20, so that a single control means such as a knob or dial may be used to effect the control of both condensers at once. Obviously this scheme of control is applied to each stage of the amplified system so that but a single control is used for each stage of amplification.
- One advantage of the invention, therefore, is that its operation is independent of the voltage distribution along the coil 3, —that is to say, since the filament of the amplifier tube is connected to the physical center of the input capacity, as shown, it is therefore connected to the electrical center of the input circuit, and hence with this arrangement there is no danger that the variation in voltage distribution along the coil may upset the balance of the Wheatstone bridge arrangement thus involved in the hook-up or circuit arrangement shown and described, which is illustrative of one form

As a further advantage, it has been found that when two capacities are connected in series, the resultant capacity variation is so greatly increased over that usually obtainable that the size of the inductance 3 may be greatly increased and the size of 8 and 9 correspondingly reduced and still cover the wave length range over which the circuit is ordinarily tunable. One advantage of this is that the voltage applied to the grid of the vacuum tube amplifier is much greater than is obtained by the ordinary arrangement, thus insuring greatly increased amplification for each stage.

It will be understood, of course, that in practice the different repeating coils or transformers will be so arranged, relatively to each other, that they will not affect each other, inductively, thereby to insure against interference between them. Furthermore, it will also be observed that with the circuit arrangement shown and described, in the grid of each vacuum tube has no metallic connection to the filament of the tube, and hence has no metallic connection to any source of direct current, and hence there is no possibility of any such source impressing its voltage on the grid. With this circuit arrangement it is found that the tone quality is also improved, over that obtained with the ordinary circuit arrangement, as the tone appears to be clearer and better, which means better and more accurate reproduction.

The expression "vacuum tube" wherever used in this specification and claims is used in a generic sense and intended to include all devices of the type adapted to amplify radio frequency currents by a voltage control of a space current.

Having thus described the invention, what I claim as new and desire to be secured by Letters Patent is:

1. Radio frequency receiving apparatus comprising a vacuum tube having a filament, a grid and a plate, an inductance, a pair of simultaneously adjustable series condensers connected in effective shunt thereto and adapted to tune said inductance to resonance with a signal, means associating said condensers whereby the adjustment of one is accompanied by the adjustment of the other, a tap from the common point of said condensers to said filament, a lead from said grid to one end of said inductance, a connection from the plate to the other end of said inductance, said connection including a capacity, and an inductance in the output circuit of said tube.
2. Radio frequency receiving apparatus comprising a vacuum tube having a filament, a grid and a plate, an inductance, a pair of series condensers connected in shunt thereto and adapted to tune said inductance

to resonance with a signal, a tap from the common point of said condensers to said filament, a lead from said grid to one end of said inductance, a connection from the plate to the other end of said inductance, said connection including a substantially pure capacity only, the said condensers being mechanically connected together to maintain a substantially fixed ratio for all adjustments thereof. 10

In testimony whereof I hereunto affix my signature.
